UNITED STATES PATENT OFFICE.

PERCY E. LONG AND WILLIAM L. SCHWARZ, OF LA CROSSE, WISCONSIN.

SEED-SEPARATOR.

1,070,350.

Specification of Letters Patent. Patented Aug. 12, 1913.

Application filed November 19, 1912. Serial No. 732,326.

To all whom it may concern:

Be it known that we, PERCY E. LONG and WILLIAM L. SCHWARZ, citizens of the United States, residing at La Crosse, in the county 5 of La Crosse and State of Wisconsin, have invented certain new and useful Improvements in Seed-Separators, of which the following is a specification.

The invention relates to gravity separators.

The object of the invention is to provide an inclined table divided into transverse spaced sections separated by transverse belts the upper runs of which receive and carry 15 off those seeds which are less spherical and do not roll so readily down the inclined sectional table; also to provide inclined throw backs on the upper side of the inclined table at the edge adjacent to the delivery ends 20 of the belts to throw back the seed that roll but which have been carried near the delivery side by the belts before reaching the next inclined table section below; also to provide means for readily raising and lowering 25 the upper end of the table to properly adjust its inclination; also to provide an efficient means for driving the several belts and imparting the proper tension thereto. These objects are accomplished by the construction shown in the accompanying drawing, in which:

Figure 1 is a perspective of the improved separator. Fig. 2 is a cross section of the machine through one of the belts. Fig. 3 35 is a like section through one of the table inclines. Fig. 4 is a detail view of one of the adjustable pulleys for the belts.

A designates uprights at the head end of the machine, and A' shorter uprights at the 40 lower end and these uprights are mounted on a suitable base A², to which they are braced by rods A³.

B is the table formed of a rectangular frame having parallel side bars b, b and end 45 bars b', b'. The lower end of this frame is hinged to the upper ends of the lower uprights A', while the upper end of the frame is provided with a transverse shaft C, the

outer ends of which pass through two slides C', C', embracing the uprights A and sliding thereon. In the outer ends of the slides C, C are guide pulleys c, c running on guides a secured to or formed on the adjacent sides of the uprights A, the opposite sides of which uprights are provided with racks a', 55 a'. The shaft C has pinions c', c' at its ends, which pinions mesh with the racks a', a', so that by turning the shaft the head end of the table B may be raised or lowered to change the angle thereof. 60

The upper or working side of the adjustable table B is formed of a series of transverse plates b², preferably of metal and spaced apart a distance to receive the upper runs of a series of transverse belts D which 65 form the traveling sections of the table. The table surface is thus formed of alternating traveling and fixed sections. The upper edges of the belts D underlie the lower edges of the fixed plates or sections b², while the 70 lower edges of the belts overlie the upper edges of the fixed sections. This construction causes the belts to have less pitch than the rest of the table surface.

One side of the table frame is provided 75 with pulleys E, one for every belt and a description of one will suffice. The pulley E is provided with a shaft e, journaled in adjustable blocks e', mounted to slide in brackets E', E' secured to the table frame b and 80 these blocks e' may be moved in or out to adjust the tension of the belt D by means of set-screws e², as clearly shown in Fig. 4. The blocks e' have depending bolts e³ extending through slots e⁴ in brackets E' and 85 on the bolts are nuts e⁵ for securing the blocks e' in their adjusted positions. At the opposite side of the table the belts pass around drive pulleys E² mounted on short shafts E³. The shafts E³ are journaled at 90 their overlapping ends in double bearings E⁴, carrying grease cups e⁶. The shafts E³ are provided with sprockets e⁷ connected by sprocket chains e⁸.

Power is applied to the shafting by means 95 of a drive pulley F mounted on a shaft F'

on the lower end of the table B and having a bevel gear f meshing with a bevel pinion e^{10} on the end of the lower shaft E^3 .

The fixed table sections or plates b^2 are provided at their ends next to the delivery ends of the belts D with throw backs or deflectors G inclined inwardly from their upper ends so as to throw back certain seeds toward the middle of the table. A hopper H is mounted on the head end of the table and this hopper may be fed from any suitable source, not shown.

It will be seen that were the belts D all driven by a single line shaft their upper runs would of necessity lie in the same plane, but by my construction the upper runs of the belts are made to lie in parallel planes, since their short drive shafts E^2 are parallel and inclined longitudinally of the side of the table. This allows the stationary plates b^2 to lie in the same plane with their upper edges underlying the lower edges of the belts D and their lower edges overlying the upper edges of the belts. The belts D, therefore, have less pitch than the stationary plates b^2 , with the result that the seeds of less roundness will be stopped by the belts and carried off, while the more perfect seed of the kind being treated will cross over the belts and roll freely across the plates b^2 which have no depressions to impede their progress. These stationary plates b^2 form a perfectly flat table surface interrupted only by the belts D, the upper runs of which have, as before stated, less pitch than the fixed surface of the table. Moreover, were the fixed portions d^2 of the table given any depressions next to the lower edges of the belts D, it would require such an elevation of the head end of the table for the round seed to run down that the pitch of the belts would then be so great that the less rounded seeds would run thereacross and not be stopped and carried off by the belts.

The operation is as follows: The table will first be set at the proper inclination or angle for the seed to be operated upon and the tension of the belts will also be adjusted. The belt driving gear will now be started and the seed allowed to flow from the hopper. Should wheat be in the hopper mixed with oats, the wheat will roll by gravity down the table and cross over the belts and fixed sections to the lower end, but the oats which do not roll so readily will stop when they reach the belts and so be carried off. Split peas and beans may be separated in like manner and so thistle and plantain from clover, and so on through many other varieties of seeds. In case certain seed, as wheat, are carried near the belt delivery side before rolling off, the throw backs G will keep them from rolling off that edge of the fixed plates and cause them to continue on down the

table. Since the belts are more nearly horizontal than the fixed sections of the table, they will readily stop and carry off those grains not so round as those which readily roll down the table as a whole.

Claims:

1. A gravity separator comprising, an inclined table formed of alternating fixed and transversely traveling sections; the former lying in substantially the same plane and the latter lying in parallel planes and having less inclination than the fixed sections.

2. A gravity separator comprising, an inclined table formed of a series of fixed plates or sections lying in the same plane and intervening feeding sections lying in parallel planes and of less pitch than the fixed sections and adapted to deliver to one side of the table.

3. A gravity separator comprising, an inclined table formed of a series of spaced fixed plates or sections lying in the same plane, and transverse endless belts the upper runs of which have less pitch than the fixed sections, lie in parallel planes and fill in the space between said fixed plates or sections.

4. A gravity separator comprising, an inclined table formed of a series of spaced fixed plates or sections lying in the same plane, and transverse endless belts the upper runs of which are in parallel planes and of less pitch than the fixed plates or sections, and said belts at their upper edge underlie the lower edges of the fixed plates and the lower edges of said belts lying over the upper edges of the fixed plates.

5. A gravity separator comprising, an inclined table formed of a series of spaced fixed plates or sections, a series of transverse endless belts the upper runs of which fill in the spaces between the fixed plates, and inclined throw backs or deflectors on the fixed plates at the ends next to the delivery ends of the belts.

6. A gravity separator comprising, an inclined table formed of spaced fixed plates and intervening endless belts, guide pulleys at one side of the table for said belts, a series of parallel pulley shafts at the opposite sides of the table, gearing connecting the adjacent ends of the shafts, and drive pulleys on said shafts for the several belts.

7. A gravity separator comprising, an inclined table formed of spaced fixed plates or sections, intervening endless belts, brackets at one side of the table, guide pulleys for the delivery ends of the belts mounted adjustably in said brackets, double bearings at the opposite side of the table, a series of parallel shafts with their ends mounted in said bearings, sprocket gearing connecting the shaft ends, and drive pulleys on the shafts for said belts.

8. The combination, with the separating

table hinged at its lower end, and uprights at the head end having racks at one side, of a shaft journaled in the head end and having gears meshing with said racks, slides extending from the ends of the shafts and embracing said uprights and rollers carried by the slides and engaging the sides of the uprights opposite to the racks.

In testimony whereof we affix our signatures in presence of two witnesses.
